UNITED STATES PATENT OFFICE.

ALBERT H. GAESS, OF WATERBURY, CONNECTICUT, ASSIGNOR TO THE E. J. MANVILLE MACHINE COMPANY, OF WATERBURY, CONNECTICUT, A JOINT-STOCK CORPORATION OF CONNECTICUT.

HEADING-MACHINE.

1,139,963.

Specification of Letters Patent. Patented May 18, 1915.

Application filed April 30, 1914. Serial No. 835,451.

To all whom it may concern:

Be it known that I, ALBERT H. GAESS, a citizen of the United States, residing at Waterbury, in the county of New Haven 5 and State of Connecticut, have invented a new and useful Improvement in Heading-Machines, of which the following is a specification.

In multiple stroke heading machines, such 10 for instance as that shown in United States Letters Patent No. 926,170 of June 29, 1909, the punch holder is given an up and down movement in the front end of the ram that is moved back and forth so that at one forward movement one punch is caused to operate on the stock held in the dies and at the following forward movement another punch operates on the stock.

The present invention relates to means 15 which are provided for locking the punch holding slide in its several positions so that when a punch strikes the stock the punch cannot be forced out of alignment and thus effect imperfect work.

20 The object of the invention is to provide a simple mechanism which will effectively lock the punch holding slide in its upper and lower positions, without danger of becoming damaged or causing any part to 25 break should anything happen to alter the timing or interfere with the proper action of the mechanisms.

In the embodiment of the invention illustrated the vertically movable punch slide is 30 stopped in its downward movement by the contact of the end of a screw which it carries with a fixed part on the horizontally movable ram by which the slide is borne and while in its lower position a locking bolt on 35 the ram is caused to engage a stud in the slide and lock the slide down. After the upper punch has performed its work the locking bolt is withdrawn and the slide lifted, being stopped in its upper position by engagement with a nut on a threaded rod that is supported by the ram. When the 40 slide is in its upper position the locking bolt is forced beneath the locking stud on the slide and holds it until after the lower

50 punch has performed its work. The engagement of the locking bolt on the ram with the locking stud on the slide in conjunction with the nut and screw positively locks the slide down and up, and the movements of the bolt are effected by the back 55 and forth movements of the ram which carries the slide, but the bolt is forced into locking position by parts which will yield and prevent breakage in case the mechanisms get out of time or any abnormal condition accidentally arises.

55 Figure 1 of the accompanying drawings shows a plan of the ram and punch slide and the mechanism for giving the former a horizontal reciprocation and the latter a vertical 60 reciprocation, and also of the mechanism for locking the slide up and down. Fig. 2 shows a vertical section of these parts on the plane indicated by the dotted line 2-2 on Fig. 1. Fig. 3 shows a side elevation of the 65 punch holding slide locked in its upper position. Fig. 4 is a similar view showing the 70 slide locked in its lower position. Fig. 5 shows an elevation looking from the rear at the upper end of the punch holding slide. Fig. 6 shows a plan of a part of the mechanism 75 employed for giving the punch slide its vertical reciprocation.

In the machine shown the ram 1 is given 80 a horizontal reciprocation in ways in the machine bed 2 by means of a connecting rod 3 and the crank 4. The slide 5 to which the punch holder 6 carrying the punches 7 is secured, is moved up and down in a way in the front end of the ram by means of a yoke 85 shaped crank arm 8 on a shaft 9 that has a rocker arm 10 which is swung back and forth by a bar 11 that is reciprocated by a cam 12 on the driving shaft 13. The ram and mechanism for reciprocating it horizontally, and the slide and mechanism for reciprocating the latter vertically, are well known and being fully illustrated in the patent previously referred to need not be more fully described herein.

90 95 At the top of the slide is a rearwardly projecting ledge 14 and turning in this ledge is a screw 15. This screw is adjusted and

then fastened by the clamp nut 16 so that its lower end will engage with the upper surface 17 of a frame 22 which is carried by the ram, for stopping the slide in exact position at the lower limit of its downward movement. Extending from the ram up through an opening in the ledge at the top of the slide is a rod 18 that is provided with nuts 19 and 20. The nut 20 is adjusted and held by the nut 19 so as to stop the slide in exact position at the upper limit of its movement. Projecting from the back face of the slide is a lock stud 21.

Movable back and forth in an opening in the upper part of the frame 22 which is fastened to the ram is a bolt 23. Engaging this bolt is an arm 24 which projects from a rocker 25 that has a roll 26 at one end and a roll 27 at the other end. Pivoted on the top of the machine bed at one side of the ram-way is a lever 28 which has on one side a projection with inclined faces 29 and 30. This lever is thrust inwardly by pins 31 and 32 which are forced against it by leaf springs 33 and 34 that are fastened to the side of the machine bed and bear against the ends of the pins. A screw stud 35 which passes through a slot 36 in the lever into the machine bed forms a stop for limiting the inward movement of the lever.

When the ram moves forward the front roll 27 on the rocker first runs up on the inclined edge 29 of the lever and this causes the rocker to swing and draw back the locking bolt. Continued forward movement of the ram causes the front roll 27 to run down the inclined edge 30 of the lever and the rear roll 26 to run up the incline 29. This swings the rocker so as to throw the locking bolt forward. When the bolt is back the slide is shifted. If the slide is up the locking bolt passes under the locking stud 21. With the parts in these positions, as shown in Fig. 3, the slide is held locked because it is held from upward movement by the engagement of the top of the ledge 14 with the bottom of the nut 20 and it is held from downward movement by the engagement of the upper surface of the locking bolt with the underside of the locking stud. If the slide is down, as it is every other time it is carried forward, the locking bolt passes above the locking stud and the slide is locked in this position, for as shown in Fig. 4 it is held from downward movement by the engagement of the end of the screw 15 with the surface 17 and held from upward movement by the engagement of the locking bolt with the upper surface of the locking stud. By this means the punch holding slide is rigidly locked in both positions so that it cannot yield when the punches strike the stock to perform their work.

As the rocker and bolt are carried by the ram and the lever which oscillates the rocker is on the bed the bolt must necessarily operate in conjunction with the locking stud at the proper times to lock the slide. However, as the lever which carries the inclines that oscillate the rocker, is held up to its working position by the spring thrust pins if anything should happen to prevent the bolt from properly passing into position above or below the locking stud the oscillating lever will yield so that no damage will result. Although the bolt rocker is positively oscillated for moving the bolt back and forth, as the ram reciprocates, by the lever which is mounted on the bed, the lever is free to yield at any time, and should one of the springs holding the pins up against the lever become broken or impotent the other will continue to perform its function of keeping the lever up to such position as to properly oscillate the rocker.

The invention claimed is:

1. The combination in a heading machine of a reciprocatory ram, a reciprocatory slide carried thereby, means for limiting the downward movement of the slide, means for limiting the upward movement of the slide, a bolt carried by the ram and adapted to co-operate with said limiting means for locking the slide in its upper and lower positions, means for reciprocating the bolt, and yielding means arranged to hold said bolt reciprocating means in operative position.

2. The combination in a heading machine of a reciprocatory ram, a reciprocatory slide carried thereby, means for limiting the downward movement of the slide, means for limiting the upward movement of the slide, a bolt carried by the ram and adapted to engage the slide and co-operate with said limiting means for locking the slide in its upper and lower positions, a rocker for reciprocating the bolt, a lever for oscillating the rocker, and yielding means holding said lever in operative position.

3. The combination in a heading machine of a reciprocatory ram, a reciprocatory slide carried thereby, means for limiting the downward movement of the slide, means for limiting the upward movement of the slide, a bolt adapted to engage the slide and in conjunction with said limiting means lock the slide in its upper and lower positions, a rocker adapted to oscillate said bolt, a wedge adapted to oscillate said rocker, pins bearing against said wedge, and springs thrusting said pins against the wedge.

4. The combination in a heading machine of a reciprocatory ram, a reciprocatory slide carried thereby, a bolt carried by the ram and adapted to lock the slide, a rocker for reciprocating the bolt, a wedge for oscil-

lating the rocker, pins holding the wedge in operative position, and springs thrusting the pins against the wedge.

5. The combination in a heading machine of a reciprocatory ram, a reciprocatory slide carried thereby, a bolt and means for reciprocating the bolt into and out of engagement with the slide, carried by the ram, a

lever mounted on the bed and adapted to operate said bolt reciprocating means, and 10 spring pins holding said lever in operative position.

ALBERT H. GAESS.
